Primary Examiner — Jennifer Rivard(74) *Attorney, Agent, or Firm* — Millen, White, Zelano & Branigan P.C.; William F. Nixon(57) **CLAIM**

The ornamental design for a hair clipper as shown and described.

DESCRIPTION

FIG. 1 illustrates a front elevational view of a hair clipper showing my new design;

FIG. 2 illustrates a rear elevational view thereof;

FIG. 3 illustrates a left side elevational view thereof;

FIG. 4 illustrates a right side elevational view thereof;

FIG. 5 illustrates a front perspective view thereof;

FIG. 6 illustrates a top plan view thereof;

FIG. 7 illustrates a bottom plan view thereof; and,

FIG. 8 illustrates a bottom plan view thereof showing a full battery graphic.

The broken lines shown throughout the views depict unclaimed portions of the hair clipper and form no part of the claimed design.
